GUMMED TAPE AND TEAR STRAND DISPENSING
APPARATUS
Arnold J. Eisenberg, Nashua, N.H., assignor to Nashua
Corporation, Nashua, N.H., a corporation of Delaware
Filed Oct. 27, 1959, Ser. No. 849,005
14 Claims. (Cl. 156—436)

This invention relates to tape and strip dispensing machines such as employed for serving adhesively conditioned lengths of tape from a supply for the purposes of packaging, sealing, labelling and such. More particularly it concerns the general class of such machines for handling moisture-activated or dry-gummed tapes.

An important object of the invention is novelly to equip machines of the class described with new and improved means whereby a rip strand or so-called tear string separately supplied upon the machine may be laminated to and combined with the main strip or tape to be dispensed in the course of the dispensing operation of the machine.

While the improvements herein concerned are adapted for use with various machines of the stated class they are particularly useful in conjunction with power-operated dispensers such as that of the Doyle, Eisenberg and McDermott application Serial No. 845,126, filed October 8, 1959, now Patent No. 3,076,586 of February 5, 1963. Hence for the purposes of the present disclosure the novel features are herein illustrated and described as adapted to and installed upon the base machine of said application Serial No. 845,126.

In the drawings illustrating by way of example one embodiment of the invention:

FIG. 1 is a plan view of the apparatus or machine as a whole;

FIG. 2 is a right side elevation of the same with a side cover plate of the control housing relating to the rip strand supply broken away;

FIG. 3 is a side elevation looking at the opposite or left side of the machine;

FIG. 4 is a longitudinal vertical section through the base machine positioned as in FIGS. 1 and 2;

FIG. 5 is an enlarged vertical section of certain feeding and severing means at the left central portion of FIG. 4, with parts omitted for clarity;

FIG. 6 is a detail horizontal sectional view as on the line 6—6 of FIG. 5;

FIG. 7 is a related detail section as on the line 7—7 of FIG. 5, looking downwardly;

FIG. 8 is a transverse section at right angles to the tape path, substantially as on the line 8—8 of FIG. 5 and on the scale of the latter, looking toward the front of the machine;

FIG. 9 is a vertical transverse section as on the line 9—9 of FIG. 4 looking toward the rear of the machine and more particularly at the tape severing means;

FIG. 10 is a vertical transverse section through the rip strand control housing as on the line 10—10 of FIG. 2 with the rip strand supply roll mainly in end elevation;

FIG. 11 is an enlarged detail section of certain severing means as upon the line 11—11 of FIG. 9;

FIG. 12 is a corresponding transverse section as on the line 12—12 of FIG. 11;

FIG. 13 is a section transverse to the tape path and in the general plane of the axes of the feed rolls, as on the line 13, 13 of FIG. 5 and looking toward the front of the machine;

FIG. 14 is a detail plan view of a central portion of a stationary blade of the severing means; and

FIG. 15 is a partly diagrammatic plan view of the leading portion of the composite tape and rip strand.

As stated, the base machine of the present embodiment is that of the identified application owned by the assignee

2

of the present application. Such machine is herein sufficiently illustrated and described for an understanding of the present invention. Unless otherwise herein stated parts including controls and circuits may be understood as being the same as in said prior application.

Referring first generally to FIGS. 1 to 4, the base machine comprises a main frame or housing 1 with side members 2 providing between them at the rear portion of the machine a holder or well 3 for the roll supply R of the dry-gummed tape T of any preferred composition and weight as appropriate for the given usage. Noting particularly FIG. 4, the tape T from the supply roll R is advanced along a path extending forwardly between the side frames to a delivery station S at the fore end of the machine, at the left on FIGS. 1, 2 and 4; at the right on FIG. 3. Advance of the tape is accomplished by a pair of opposed separable rotary members including a driven lower feed roll 6 and an upper feed or pinch roll 7 later referred to in further detail. The herein lower feed roll 6 is driven by an electric motor M, FIGS. 1 and 3, and through reduction gearing in the adjacently located gear housing 8 as in said application and in the commonly owned Patent No. 2,776,833 of January 8, 1957, reference to which may also be made for further illustration and description of the main feeding, moistening and severing devices of the base machine.

As seen in FIG. 8 the driven lower feed roll 6 is fixed on a shaft 6a journaled in a lateral boss on the machine frame, the shaft extending into the gear housing 8 and there drivingly connected as at 6b with the mentioned motor-driven train of gearing. The upper or pinch roll 7 of the roll pair which also serves as a tape length-measuring element is mounted on a transverse shaft journaled in a sleeve 7a on one arm 7b of a bellcrank rockably mounted on a transverse shaft 11 supported on and between the machine side frames 2. The other arm 7c of the bellcrank, of which the upper portion only is seen in FIG. 8, is connected to an actuator for movement normally to open and at each operating cycle to close the pinch roll 7 into tape feeding relation with the driven roll 6. As in said mentioned application and said Patent 2,776,833 such actuator comprises a spring-loaded reciprocable rod 16 connected at one end to a solenoid indicated generally at 15, FIGS. 1 and 2, and at the opposite forward end operatively engaged with said depending arm 7a of the pinch roll bellcrank. Such actuator 16 also is connected with one arm of a second bellcrank, the other arm of which is operatively connected to a generally vertical link 18, FIGS. 4 and 9, by which the movable blade 20 of the severing means is elevated or depressed in tape severing coaction with the fixed blade 30.

Again noting FIG. 4 the path of the main tape T from the supply roll R in the housing well 3 extends forwardly between the feed and pinch rolls 6, 7 and along between lower and upper guides 14, 14' past the severing blades 20, 30 and beneath an adjustably weighted platen 19 overlying brush moistener means B projecting from a liquid reservoir 12 removably set on cross supports on and between the front portions of the machine side frames 2. As shown the level of the liquid in the reservoir is maintained in known manner from a replenishable supply in an automatic feeding container or flask 13 demountably held herein at the left side of the machine, FIGS. 1 and 3. The reservoir may be equipped with a heater 190 for the tape-moistening liquid, the electrical connections for which heater are seen in FIG. 3.

In connection with the foregoing it is noted that the base machine, similarly as in said application Serial No. 845,126 is equipped with detachable plug-in type connections with the power supply and for the several operating and control circuits of the machine. Such provisions include an outlet block 100 at the left lower central portion

of the machine frame, see FIG. 3, including a socket portion marked "Heater Side" for plug-in reception of the mentioned heater or other accessory, and a socket portion herein marked "Switch Side" for plug-in connection of the circuit-forming leads of one or another operator-controlled cycle-starting switch such as the extended-area arcuate manual switch bar 170 similar to that of said prior application.

Such circuit-forming connections also include a plug-in receptacle 200 for the circuit connections of the cycle-terminating trip switch (not shown) whereby the tape feed is halted and the tape severed upon delivery of a pre-selected measured length of the tape, as in the mentioned application. The manual grip or knob 163 of the length selector arm 164 are seen in FIGS. 1 and 2, the selector mechanism in the illustrated example being of a construction and arrangement including a rotary numbered drum 55 whereby selected length values for the tape are viewed and selectively set at a window 59 on the arcuate flange of the control housing side cover plate 5 within which the length-numbered drum 55 is outboard mounted for proportioned and calibrated drive from the upper feed roll 7.

The foregoing description in connection with the drawings and with reference to the earlier disclosures herein identified sufficiently explains the general construction and arrangement of the base tape-dispensing machine for an understanding of the combination and co-operative relation therewith of the tear strand incorporating means of the present invention. While such means is useful with other constructions of gummed tape dispensing machines it is herein particularly adapted for installation as auxiliary equipment for the described multi-use or universal machine having plug-in type electrical connections for different operating controls and accessory items, so that the tear string supplying mechanism may readily be removed when not desired for use. The construction and arrangement also is such that with the tear-string supplying devices installed the machine will accept and dispense tapes not having a tear-string, or tapes having tear-strips preapplied, as well as being able to laminate a tear-string to whatever tape is desired to be dispensed as use requirements dictate.

The general purposes and functions of a pull-strand or "tear-string" in assisting removal or ripping of adhesively applied tape in opening packages, cartons and the like to which it has been applied are well known. By grasping such tear-strand at an end portion of the applied tape and pulling back against the overlying tape the latter may be ripped or pulled free to afford access to the package. Such strand itself, one example of which is herein designated generally by the reference character P, may be variously formed of any suitable material to provide a relatively narrow continuous member of substantially equal flexibility with the main tape and of a strength suitable for the stated purposes, whether formed as a string or cord or as a narrow tape individually fabricated or slit to width from wider web. In general it is desirable that consistent with the strength requirements such strand be flat or flattened and of limited thickness to afford little or no hindrance to normal adhesive use of the tape with which it is to be employed. The tear-strand P as herein illustrated may be regarded as typical for the purpose. One commercially available example of such tear strand with which the equipment of the illustrated embodiment has been satisfactorily employed is that composed of a multiplicity of longitudinal threads or filaments adhesively bonded together or united by a carrier vehicle to form a $\frac{1}{8}$ inch unbleached tape identified as "No. 121" as supplied under the trade name "Print-Ad-String." The element P as herein represented may be assumed to be such narrow tape or composite strand.

In FIGS. 1 to 3 and 10 a supply package of the tear strand is shown in the form of a roll or spool thereof PR. As thus supplied the tear-strand P is wound upon a spool having end heads 70, 70 including supporting

journal plates 71 axially apertured in line for reception of a spindle 85 later referred to. The spool head bearer plated 71 have one or more radially offset locking apertures 72 whereby the spool may be locked on and to turn as a unit with the spindle 85.

This tear-strand supporting spindle 85 is rotatably mounted at one end on a longitudinal rearward extension of one of the side frames 2, herein that at the right, of the base machine 1; see FIGS. 1, 2 and 10. Such extension comprises a generally rectangular housing compartment 80 with an inner longitudinal side wall 81, a top wall 82, end walls 83, 83' and a removable outer side wall or cover plate 84. This housing as a unit is demountably secured at its front end to the adjacent machine side frame 2 as by bolts 81a extending through the inner side wall 81 and into fixed part of the machine.

Noting particularly FIG. 10, laterally aligned apertures on the inner and outer side walls 81 and 84 have disposed thereon anti-friction bearing rings 86, 87 in which the adjacent end of the spindle 85 is rotatably received and operatively positioned in laterally extending horizontal position for holding the tear-strand supply roll PR for rotation with its axis parallel to that of the supply roll R of the main tape T and with the roll supplies in tandem relation and generally in line with each other lengthwise of the machine.

From the roll supply package PR on the described auxiliary unit 80 the tear-strand P travels forwardly into the base machine 1 at the rear and lower portion of the tape well 3 as through the space 310, FIG. 4, between the lower rear end of the rear top cover 3a and the arcuate plate 3b providing a bottom closure for said tape well 3. Alternatively the strand P may enter the well through a special port for it in said bottom plate 3b. As best seen in FIG. 4, this tear-strand P after entering the well 3 passes forwardly below the position of the main tape roll R, being guided beneath transverse rollers 311, 312, 313 on which the main tape roll R is rotatably positioned in the well, partly about a further guide roller 314 and in front of another transverse guide member and cross-support 315 to and through a special moistening device 120 to be described and into paralleling position along and at the underface of the tape T to which the strand P is to be laminated at the feed rolls 6, 7 by which the strand P is advanced from the supply thereof in synchrony with the main tape T.

For proper tensioning of the tear-strand P and to avoid overrun, control means therefor is provided in operative association with the spindle 85, within the auxiliary housing compartment 80. Noting again FIGS. 2, 3 and particularly FIG. 10, the spindle 85 has fixed on it as by a set screw a collar 88, inwardly beyond the inner compartment wall 81, limiting endwise movement of the spindle toward said wall and adapted to abut the adjacent spool head 70 and bearing plate 71. Said collar 88 has at the face adjacent the spool a projecting pin 89 paralleling and radially offset from the axis of the spindle 85. This locking pin 89 is receivable in any of the series of locking apertures 72 previously mentioned in the tear-strand spool heads 70, 70 or the journal plates 71 thereof. The spindle 85, collar 88 and the strand spool accordingly are adjusted to rotate as a unit.

Within the auxiliary compartment 80 the spindle carries a drum or sheave 90 having a hub 91 with a set screw for affixing the sheave on and to turn with the spindle unit. Aligning bearing for the adjacent outer end of the spindle is provided by the mentioned anti-friction or ball-bearing ring 87 on the cover plate 84. The sheave normally holds the spindle against axial shifting in the direction away from the compartment wall 81, toward the right on FIG. 10.

The mentioned tensioning torque and anti-overrun control for the spindle and strand package thereon is afforded through the medium of said drum 90. As seen in FIG. 10 it is formed with a peripheral channel, shown as of

V-form similarly as on pulleys for V-belts. As seen in FIG. 2 and also FIG. 10 there is mounted in the compartment a spool-loading or tensioner arm 92 pivoted as at 93. The arm 92 has at the rear end a thin upstanding shoe 94 adapted to ride on the bottom wall of the groove of the drum or sheave 90. The shoe 94 is of selected fibrous or other material to bear with limited frictional gripping against the sheave and so as to provide appropriate torque-resistance to turning of the spindle in the strand feeding direction to prevent the spool thereof from paying off the strand P too freely in the course of a feeding cycle. This tensioning or retarding of the spool is ordered as appropriate by the loading spring 95 fixed at one end intermediately on the tensioner arm 92 and at the other end to a stud 96 on the compartment wall 81. Said tensioner arm 92 is actively engaged with the drum 90 and spindle 85 at all times.

For positively halting the turning of the spooled strand package PR at the end of a feeding cycle additional on-and-off brake means is provided, to be released for and during feed of the strand P and to be sharply reapplied for quick stopping of the strand package when the feed is terminated.

As herein illustrated such means comprises a brake lever 97 rockably mounted intermediate its ends on the stud 96 previously mentioned. At the rear end over the drum 90 this brake lever 97 carries a brake shoe 98 of a semi-rigid or other gripping composition and shaped with a down taper for gripping against the walls of the V-groove of the shive similarly as with V-belts. A spring 99 of selected weight for positive brake application urges the brake lever 97 and shoe 98 into on or applied position, being connected at the upper end to the rear end of the lever and being anchored at the lower end as at 99' to a lug on a housing wall.

For releasing the spool-halting brake means 97, 98 at the start of each feed cycle and to hold it in "off" position during such cycle there is provided in the compartment 80 electro-magnetic means shown as a solenoid 301 having an armature 302 with a link 303 connecting it to the fore end of the brake lever 97. This solenoid is adapted and arranged for electrical connection into the power supply and control circuits of the machine through a circuit conductor cord 304 equipped for detachable plug-in connection at the circuit junction box 300, see FIG. 1, of the base machine similarly as described for certain relay means of the base machine in the mentioned application Serial No. 845,126. When the electrically connected brake-release solenoid 301 is subject to the power and control circuits so that when the operator depresses the cycle starting switch bar 170, FIGS. 1 and 2, to start a feed cycle by actuating the motor M and the solenoid 15 for the actuator 16 which causes the feed rolls 6, 7 to close into feeding relation to the tape T and the tear-strand P, then simultaneously the strand brake solenoid 301 is activated. It accordingly pulls down the front end of the brake lever 97 and lifts the brake shoe 98 out of braking engagement with the shive 90 of the strand-package-holding spindle 85. Conversely, at the end of a feed cycle, when the tape length selectively set by the selector arm 163, 164 has been fed out and the circuit tripped by the automatic cut-off switch associated with the length-measuring means, then at the same time the brake solenoid 301 is de-energized and the brake means 97, 98 is immediately applied by its spring 99 quickly to stop turning of the spool package. Thus even transverse alignment for the leading ends of the tape T and tear-strand P is continuously maintained.

Mention has above been made of means for adhesively conditioning or moistening the tear-strand particularly at the upper face for secure lamination thereof to the under face of the tape T at the same time if desired rendering adhesive the under face of the strand for adherence thereof to the package or article to which the laminar tear-strand and tape unit is to be applied.

For this purpose there is herewith provided on the machine at a location along the strand path but behind the rotary feed means 6, 7 the mentioned means for rendering the tear strand P adhesive while en route to the feed means. In the illustrated example such tear-strand moistener provisions comprise a demountable sub-assembly 120 including a liquid receptacle or auxiliary reservoir 121 herein at the left side of the machine, FIGS. 1 and 3, behind the main moistener reservoir 12 and liquid supply flask 13 and forward of the motor M. In this receptacle 121, having a removable cover 122, is placed one end portion of an elongate absorbent wick 123 of felted fibrous or like material. The wick projects through a wall opening of the reservoir and in through a port 124 on the adjacent side frame 2 of the machine to a position adjacently below the rear part of the lower tape guide 14 and behind the feed rolls; see FIGS. 4 to 7.

At the stated location the front upper end of the tape well floor plate 3b is formed centrally thereof with a notch 3x at and horizontally across which is affixed as by screws or rivets a channeled wick holder or clip 125, seen in vertical section in FIG. 5 and in top elevation in the horizontal sectional detail view, FIG. 6, looking down on the line 6—6 of FIG. 5. The wick 123 entering the machine housing at the port 124, FIG. 3, extends across horizontally to the central longitudinal vertical zone of the machine passing along the front face of the tape well bottom plate 3b to the notch 3x thereof through which it is deflected rearwardly, FIG. 6, into the channeled portion of the holder clip 125, see also FIG. 5. Thus a portion of the wick 123 is presented in a vertical plane in the path of the tear-strand P as it travels upward from within the well 3, so that the wick has moisture-applying relation to the tear-strand P for wetting the latter at least 35 at that face which is to come into direct laminating engagement with the gummed underface of the tape T. Said laminating face of the strand P, sometimes also other surface thereof, may itself present a normally dry moisture-activatable adhesive such as that of the gummed face of the tape T so as to be activatable to adhesiveness by the applied moisture from the auxiliary wick 123, for extra adhesive bonding with the gummed tape T which in turn is adhesively activated at the strand-receiving zone through transfer of some of the moisture from the strand P thereto; or said laminating face of the strand P if without a moisture-sensitive adhesive is such as to serve as a wettable receiver and carrier of moisture from said wick 123 for activating transfer thereof to the gummed face of the tape T and attendant laminating adherence of the strand P thereto. In the moistening travel of the generally thin tear-strand P upwardly across the wick 123 the edges as well as the then (FIG. 5) rear face thereof are usually wetted. Also the then front face, that which will remain exposed at the underface of the tape T following subsequent laminating travel through the feed rolls 6, 7 may be moistened by the wick moistener 123, the inner end of the latter if desired being turned back upon itself to form a loop of wicking through which the strand passes and receives all-over moistening treatment. For most uses application of moisture by the auxiliary moistener 123 only at the laminating face of the strand P is sufficient and may be preferred by the user.

Immediately above the wick moistener 123 the moistly conditioned or adhesively activated tear-strand P, as the case may be, passes forwardly over the down deflected transverse rear lip 14a of the under guide plate 14 at which the tape T and the tear-strand P come together and travel in close parallelism in flatwise juxtaposed relation for laminating them securely together at the feed rolls 6, 7. For directing the tear-strand P into accurately longitudinally centered, or other desired positioning widthwise of tape T the strand P is lead through an aligning or centering guide 130, FIGS. 4, 5 and particularly FIG. 7, shown as a loop member with legs spaced by approximately the 75 width of the strand P so as to straddle the path of the

latter. This guide is operatively located by a transverse rod 131 extending between the machine side frames and supporting the rear end of the lower tape guide plate 14. The latter is formed with a slot for the suide 130, at or near the juncture with the downwardly deflected guide lip 14a. Moisture protection for the latter and the guide plate 14 along the path of the strand P and a good traction surface thereat may be provided by a coating or applied layer 132, FIG. 7, of appropriate plastic, rubberous or friction tape or the like.

For equal synchronous feed of the pull strand P along with the tape T and for even and secure lamination of the two of the feed rolls 6, 7 are specially formed peripherally and novelly cooperate in the feed action. As best seen in FIGS. 8 and 13, the lower and driven feed roll 6, having a tubular hub 6h with set screw by which it is interchangeably mounted on the roll shaft 6a. The special roll 6 as shown installed is formed with a central peripheral zone 61 of larger diameter presenting an annular raised band of a radial depth approximately equal to the thickness of the pull strand P to be laminated to the adhesive face of the tape T. This raised zone 61 has knurling 62 upon the peripheral face thereof, as does also the two portions of lesser diameter of the roll, as indicated at 63, 64.

For cooperation with the described lower roll 6 the upper roll 7 has the periphery formed with an annular central recess 75 into which is set substantially flush with the circumferential surface of this roll 7 a tire 76 of somewhat yielding resilient or semi-rigid rubberous or other composition of a low hardness of about the order of 50 Durometer. The higher band 61 of the lower roll 6 and the tire 76 of the upper or pinch roll 7, which is positively closed into pressing feed-effecting relation with the lower roll 7 by the actuator of the solenoid 15 at the start of a feed cycle, both parallel the path of the pull strand P and hence are effective at the opposite faces of the strand to force it flatwise into firm laminating application to the tape T. In this action the strand P and the opposed central longitudinal zone of the tape T are 40 radially offset by the high zone 61 of the roll 6 and cause the tire 76 of the upper roll 7 to be correspondingly compressed substantially as illustrated in FIG. 13. This action not only insures a firm grip of the rolls upon both the tape T and the strand P for equal feeding, but also causes said engagement to take place with the strand P moving in the same plane as the body of the tape T at the portions to both sides of the strand P. Thus at the region of feeding engagement of the rolls upon the composite laminar strip consisting of the tape and the strand, both elements T and P thereof are engaged at equal radial distances from the axes of the rolls and hence receive equal imparted linear travel in unison. Therefore both the tape T and the strand P are drawn off from their respective supplies at the same rate and are laminated together with minimal or zero shearing action between them as would be caused by uneven feed and interference with proper interbonding. Thus the synchronously and equally traveling tape T and strand P are laid together in a manner promoting a secure adhesive bond between them.

Behind the feed rolls may be provided anti-retraction means which may be as in the mentioned application, comprising a finger 140 supported for pivoting on a horizontal axis as at 140a and lightly spring loaded in the counter-clockwise direction, FIGS. 4 and 5. In the direction of the tape feed the finger readily yields for tape travel below it, but under attempted opposite retraction of the tape the finger at the eccentric lower end pinches on to and holds the tape.

The composite strip or web comprising the tape T with the pull strand P laminated upon its gum-coated under face is advanced by and between the feed rolls 6, 7 forwardly along and between the guides 14, 14' to and across the main severing means comprising the vertically mov-

able blade 20 and the fixed blade 30 earlier mentioned, FIGS. 4, 5, 9 and 11, and beyond these is advanced across the brush moistener means B in moistening relation thereto under the controlled downward pressure of the adjustably weighted platen 19, and issues at the delivery station S in adhesively condition for application, in generally similar manner as in the mentioned application.

To facilitate the use of the tape and laminated tear-strand P means may be provided for forming at the leading marginal portion of the delivered tape lengths an easily freeable grasping tab piece to be seized for ripping out through the applied tape T. As illustrated in FIG. 15 such tab PT is defined between short generally longitudinal punches or lines of weakening or separation within the severed end of the tape T, as at small-case letters J.

The transverse cut-off means for the tape comprises the mentioned movable knife blade 20 which may be as in identified application, of the guillotine type having the cutting edge in the form of an inverted shallow V, straddling the tape path, FIG. 9. In the quick down stroke of this knife effected in relation to the completion of the tape feed and on a part of each operating cycle, the shearing of the tape progresses inwardly from both sides toward the center of the tape by reason of the V-form of the knife, with the central zone accordingly cut last. The mounting and operating connections for this guillotine knife 20 include the vertical link 18 connected for down movement by the actuator 16 upon deenergizing of the solenoid 15 at the end of the operating cycle. The two-part knife 20 is removably attached to a transverse carrier bar 21 on a foot plate 22 of a guide post 22a, the bar 21 being pivotally hung at the ends on depending links 21a of the knife support yoke 21b rockable on a cross-shaft 21c on the machine frame similarly as in said prior application, said yoke in turn operatively connected to said vertical actuator link 18. The guillotine knife 20 biased by a spring 20s shears the tape T and tear-strand P transversely against the fore edge of the fixed blade 30.

The mentioned tab-forming punch lines J, J may be variously formed. For the purpose there is shown in FIGS. 9, 11 and 14 auxiliary piercing means structurally separate from the guillotine blade 20 and detachably mounted on the carrier bar 21. The latter has a notch at its under face to receive an inverted U-shaped double-pointed punch or punch-cutting element 23 having legs 23a, 23a spaced crosswise of the tape path and formed at the lower rear corner portions with punch points 24, 24. This punch unit is set up into the notch of the carrier bar 21 and there demountably held as by a screw 23b, FIG. 12, extending through the base of the U. From the piercing points 24 the legs 23a, 23a incline upwardly and forwardly as at 25 to a level above the adjacent edge of the guillotine knife 20, as indicated at 26 on FIGS. 11 and 12, and may be bevelled for cut-punching coaction with the tape T upon opposite sides of the tear-strand P. For cooperation with the punch legs 23a the stationary blade 30 of the machine is formed with a like spaced pair of narrow vertical openings or recesses 31, 31 of major area at the inner or rear ends at 32, 32, FIG. 14, to receive the punch points 24, 24 and herein tapering forwardly toward or to the front edge of said fixed blade 30.

From the foregoing in connection particularly with FIGS. 9, 11, 12, 14 and 15 it is seen that while the punch points 24 of the auxiliary unit may pierce the tape T only after cross severance thereof by the guillotine blade 20 has begun and moved in from the tape edges, the subsequent longitudinal punch-cutting action of the punch legs 23a, 23a progresses from the points 24, 24 forwardly and in the direction of the tape feed and either stops short of or meets the front edge of the tape after the last-severed central zone of the tape has itself been transversely cut, leaving if desired, a thin and easily broken link or score line of the tape across the front edge of the

tape at the punch lines 1, 1, FIG. 15, serving in use to retain the tab flatwise against unintended premature displacement of the tab PT and the strand P joined with it. It will be understood that the described grasping piece PT is left formed with the forward cross severed edge of the leading end of the tape T that is left in the machine following each operating cycle, so as to be available at the fore end of the next tape length to be fed, laminated and delivered in adhesive condition for application in use.

It will be understood that the tear-strand P as described may be impregnated with or have at least at the laminating face thereof a coating of a normally dry gum or the like suited for adhesive conditioning by moistening thereof by the auxiliary moistener wick 123. In other instances the strand P itself may be non-gummed or substantially so and formed to present a moisture-receiving and carrying surface structure or texture adapting it to pick up and carry with it moisture from the wick which on laminating contact of the strand with the opposed moisture-sensitizable face of the main tape T renders the latter sufficiently adhesive along the medial zone at which the strand P joins with it to effect adhesive bonding and lamination of the strand to the tape as the two progress synchronously through between the described feed rolls such as 6 and 7.

My invention is not limited to the particular embodiments thereof illustrated and described herein, and I set forth its scope in my following claims.

I claim:

1. In a gummed tape dispensing machine having a housing frame with tape roll rotatably supporting means, opposed rolls for feeding the tape, moistening means for the gummed face of the tape, transverse severing means for the tape between the feeding and the moistening means, and operating and control provisions for all said means for effecting successive cycles of tape feed, moistening and severance; in combination therewith a rearward extension of the machine frame, a spindle rotatably mounted on the extension for holding a spooled supply of a tear-strand in tandem relation to the tape roll, guide means for such strand directing it into the tape path rearwardly of the feed rolls for parallel travel with the tape medially of the adhesively conditionable tape face, auxiliary moistener means also rearwardly of the feed rolls for applying moisture to the strand before face-contacting entry thereof into the tape path en route to the feed rolls, and opposed strand-thickness compensating medial peripheral formations on the feed rolls at the path of the strand for feeding the tape and the strand synchronously at the same linear rate for adhesively laminating the moistened strand to the adjoined face of the tape, said medial peripheral formations comprising a raised zone on one feed roll and on aligned compressibly yielding zone on the other feed roll.

2. In a tape dispensing machine according to claim 1 the combination including double-pointed punch means straddling the strand path adjacent the tape severing means and synchronized therewith for punch-forming a grasping piece in the leading margin of the tape remaining on the machine after each operating cycle.

3. A gummed tape dispensing machine according to claim 1 including a drum fixed on the strand holder spindle, torque resisting means engageable with the drum for tensioning the strand in feeding thereof, brake means cooperable with the drum for stopping turning of the spindle and strand supply thereon against overrun of the strand at the end of a tape and strand feeding cycle, spring means for normally applying the brake means, and electro-magnetic means for releasing the brake means at the start of and during each feeding cycle, the operating and control provisions for the feed rolls and the severing means being electrical and the machine housing frame being equipped with a power-supplied electrical circuit junction box with plug-in type receptacle, and the electro-magnetic means for operating the brake means in

cluding an electrical conductor cord connected thereto at one end and having plug-in connection at the other end for attachment at said receptacle.

4. In a tape machine for dispensing lengths of gummed tape having a tear-strand adhesively applied lengthwise along and centrally of the gummed face and in which machine said tape is to be advanced along a longitudinal path to and past a moistener for the gummed face thereof, a longitudinal housing frame mounting guide means defining said path for said tape, said frame also rotatably mounting at an intermediate location in said path an opposed pair of feed rolls for advancing said tape between them and along said path, said feed rolls having in line with the tear-strand of the tape as advanced along said path medial peripheral formations for strand-thickness compensation in the feeding of the tape between them, said peripheral formations comprising a medial raised zone on one feed roll and an aligned compressibly yielding zone on the other feed roll of said pair.
5. For installation on a gummed tape dispensing machine having a housing frame with means at a rear portion thereof for rotatably supporting a tape supply roll, opposed rolls for feeding the tape between them, moistening means for the gummed face of the tape, transverse severing means for the tape between the feed rolls and the moistening means, and electrical operating means with power-supplying and control circuitry for said feed rolls and severing means for effecting successive cycles of feed, moistening and severance of lengths of the tape; a tear-strand supplying assembly comprising a generally rectangular housing compartment connectible at the rear of the machine frame in laterally offset relation to the longitudinal center line of the tape path thereon, said compartment having laterally spaced side walls, a strand package holding spindle having one end journaled in aligned bearing apertures on the compartment side walls, the body of the spindle projecting from the compartment and horizontally across the machine, a sheave-like brake drum fixed on the spindle within the compartment, a rockable brake lever and shoe thereon for braking engagement with the spindle drum, spring means normally urging the brake lever into braking relation with the drum, a solenoid and armature operatively connected to rock the brake lever for releasing the shoe from the drum and circuit leads for the solenoid for connection thereof into the power-supplying and control circuitry of the machine.
6. The tear-strand supplying assembly according to claim 5 including a tensioner shoe in the compartment and engageable with the brake drum, a pivoted arm carrying the shoe and spring means effecting yielding engagement of the shoe and drum for tensioning the strand during pay-off from the spindle-carried package thereof.
7. For installation a gummed tape dispensing machine having a housing frame with means at a rear portion thereof for rotatably supporting a tape supply roll, opposed feed rolls forward of the tape roll supporting means and adapted to advance the tape between them, moistening means for the gummed face of the tape comprising a main liquid reservoir with a projecting brush moistener adjacent the front of the frame, transverse severing means for the tape between the feeding and the moistening means, and operating control provisions for said feed rolls and severing means for effecting successive cycles of tape feed, moistening and severance; a supplemental liquid reservoir mountable externally on the machine frame intermediate the ends thereof, an elongate wick having one end received in said reservoir, the wick extending from the reservoir and laterally into the machine housing to a position below the tape path and rearwardly of the tape feed rolls, holder means for the extended portion of the wick in the machine housing, said wick holder means adapted for mounting on a fixed transverse member on the housing frame rearwardly of the feed rolls, and guide means on a cross-member of the frame for directing a longitudinal tear-strand from a rearwardly lo-

cated supply thereof across and with at least the upper face of such tear-strand in moisture-receiving relation to the wick and thence forwardly to and through the feed rolls with the tear-strand over the driven feed roll and between it and the tape and with said moistened upper face of the tear-strand against the gummed down-directed face of the tape for laminar adhesive bonding of the strand to the tape during said passage thereof from the wick to and through between said feed rolls of the tape dispensing machine.

8. In combination, in a gummed tape dispensing machine having a housing frame with tape roll support means, opposed rolls for feeding the tape, moistening means for the gummed face of the tape, transverse severing means for the tape between the feeding and the moistening means, and operating and control provisions for said means for effecting successive cycles of tape feed, moistening and severance, said severing means comprising a guillotine blade downwardly movable across the tape path to shear the tape against a fixed blade, the movable blade being of shallow inverted V-form and the machine having a movable blade carrier including a cross bar to which the movable blade is secured and having operating means for the carrier to effect down cutting action of such movable blade; a punch-cutting device for forming a grasping piece at the forward margin of the tape remaining in the machine upon severance of a delivered tape length therefrom, said device comprising an inverted U-shaped punch element having sharp pierce-punching points at the lower rear corner portions of the U-legs and having the bottom edges of the legs inclining forwardly and upwardly, and means for attaching said device to said cross bar of the blade carrier with the punch points positioned toward the rear of the machine and located and laterally spaced to straddle a central longitudinal zone of tape fed forwardly below it, and said fixed blade having in vertical line with the U-legs of said punch device a like plurality of longitudinal slots of larger horizontal area at the rear thereof adapting them to receive the down-projecting points of said legs and extending forwardly for following reception of at least a portion of the forwardly and upwardly inclined bottom edges of said legs thereby to cut-form said tape-grasping piece progressively forwardly in the direction of the tape feed.

9. In combination, in a gummed tape dispensing machine in accordance with claim 8 wherein the U-legs are spaced transversely of the tape path to an extent adapting them to straddle the path of a tear-strand centrally longitudinally laminated to the main tape so as to pierce-punch the tape in said forwardly progressive manner at the opposite longitudinal sides of the tear-strand for inclusion of the latter with the tape and strand-grasping piece so formed.

10. A gummed tape dispensing machine according to claim 1 wherein the rearward extension of the machine frame comprises a generally rectangular compartment offset from the longitudinal center line of the machine and having laterally spaced side walls, the strand supply holding spindle having one end journaled in aligned bearing apertures on said compartment side walls, the body of the spindle projecting from the compartment and horizontally across the machine, a sheave-like brake drum fixed on the spindle within the compartment, a rockable brake lever and shoe thereon for braking engagement with the spindle drum, spring means normally urging the brake lever into braking relation with the drum, and means to rock the brake lever for releasing the shoe from the drum during active operation of the feed rolls of the machine.

11. In a tape machine according to claim 1, the combination wherein the tape severing means comprises an inverted V-form guillotine blade downwardly movable across the tape path and a fixed blade coacting with the movable blade to shear the tape, a carrier on the machine for the movable blade including a cross bar to which

said blade is secured and carrier operating means to effect cutting action of such blade, punch-cutting means for forming at the forward margin of the tape remaining in the machine a grasping-piece including the then forward portion of the tear-strand, said means comprising an inverted U-shaped punch element having sharp pierce-punching points at the lower rear corner portions of the U legs thereof and with the bottom edges of said legs inclining forwardly and upwardly, said means attached to said cross bar of the movable blade carrier in position to straddle the longitudinal zone of the tape at which the tear-strand is located, and said fixed blade having in vertical line with the U-legs of said punch device a like plurality of longitudinal slots of larger horizontal area at the rear thereof adapting them to receive the down-projecting points of said legs and extending forwardly for following reception of at least a portion of the forwardly and upwardly inclined bottom edges of said legs thereby to form said tape-grasping piece progressively forwardly in the direction of the tape feed.

12. In a tape machine for dispensing lengths of gummed paper tape having applied lengthwise along the gummed face a tear-strand and in which machine the tape is fed and delivered along a substantially horizontal path across a moistener with the gummed face down; a cut-off blade movable in a vertical plane across the tape path and having a cutting edge for severing a fed length of the tape and tear-strand, and tab-forming means disposed intermediately along said cut-off blade at the rear transverse vertical face thereof and mounted for movement therewith, said tab-forming means comprising punch-cutting legs spaced to straddle the tear-strand and operative in vertical planes substantially normal to the plane of the cut-off blade to form slits in the tape adjacent and paralleling the tear-strand and lengthwise of the tape, each leg having a punch-cutting end adjacent the tape path with an initial tape-engaging point at a rear corner of the leg and a cutting portion extending forwardly from said point and inclined away from the tape path for progressive longitudinal forward cutting of the tape, and the forward end of said cutting portion being vertically spaced relative to the adjacent portion of the cutting edge of the cut-off blade in the direction away from the tape path so that the cross severance of the tape and tear-strand is accomplished before completion of the forward cutting of the slits.

13. In a tape dispensing machine according to claim 12 the construction wherein said slit-forming legs are spaced rearwardly of the cross cut-off blade sufficiently to leave a readily breakable unslit link of the tape across the front edge thereof at the slit location.

14. In a tape dispensing machine according to claim 12 the construction wherein the cutting edge of the cut-off blade is in the form of a shallow V with the apex thereof 55 away from the tape path, and the tab-forming means is located at the region of said V apex.
